United States Patent Office

Des. 175,183

Patented July 19, 1955

175,183

EAR MUFF OR THE LIKE

Bernard Millinger, Brooklyn, N. Y.

Application October 11, 1954, Serial No. 32,612

Term of patent 7 years

(Cl. D3—2)

FIG. 1.

FIG. 2.

FIG. 3.

Fig. 1 is a front elevational view of an ear muff or the like, showing my new design.

Fig. 2 is a side elevational view.

Fig. 3 is a top plan view thereof.

I claim:

The ornamental design for an ear muff or the like, substantially as shown.
